UNITED STATES PATENT OFFICE.

DAVID GOLDSMITH, OF NEWARK, NEW JERSEY, ASSIGNOR TO L. GOLDSMITH & SON, OF NEWARK, NEW JERSEY, A FIRM COMPOSED OF DAVID GOLDSMITH, NATHAN GOLDSMITH, AND DAVID OSTERWEIL.

WARDROBE-TRUNK.

1,174,565.

Specification of Letters Patent.

Patented Mar. 7, 1916.

Application filed September 17, 1913. Serial No. 790,170.

To all whom it may concern:

Be it known that I, DAVID GOLDSMITH, a citizen of the United States, and a resident of Newark, in the county of Essex and 5 State of New Jersey, have invented certain Improvements in Wardrobe-Trunks, of which the following is a specification.

The objects of this invention are to provide a swinging support for the garment 10 hangers which shall be firm and strong and which shall strengthen the trunk; to secure an improved pivotal head for the attachment of the garment hangers to said swinging support; to provide a bracket upon the 15 back of the trunk for supporting the free ends of the hangers when closed into the trunk; to secure simplicity of construction and operation, durability and freedom from getting out of order, and to obtain other 20 advantages and results as may be brought out in the following description.

Referring to the accompanying drawings, in which like numerals of reference indicate the same parts throughout the several 25 views. Figure 1 is a perspective view of a wardrobe trunk embodying my improvements, the same being shown open to receive garments and with a portion of its wall broken away to disclose the bracket above- 30 mentioned; Fig. 2 is a transverse section of a portion of the trunk taken just above the swinging support and showing the same with the garment hangers removed; Fig. 3 is a detail plan of the swinging support in 35 closed or folded position and removed from the trunk body; Fig. 4 is a detail longitudinal section through the pivoted end of a garment hanger, on line A—A, Fig. 5, and Fig. 5 is a perspective view of one of the piv- 40 otal heads for the hangers.

In said drawings, 1 indicates the wardrobe section of the trunk and 2 its packing section, said wardrobe section having a back 3, sides 4, 5, and top 6 and bottom 7. To 45 the side wall 4 next the packing section 2, and near the top 6 of the trunk, is applied a swinging support 8 adapted to open forwardly into substantially the plane of the front of the wardrobe section, as shown in 50 Figs. 1 and 2, and to close rearwardly against the side wall 4. To this swinging support 8 are hinged a series of garment hangers 9, to receive garments as illustrated by the trousers 10 in the drawing. In use, said 55 garment hangers project from the wardrobe

section, as shown, but when for shipment the support 8 is closed inward the hangers lie parallel to the back 3 of the trunk, preferably with their free ends over a bracket 11 shown in Fig. 1 and hereinafter described. 60

In the particular form shown, the support 8 comprises a leaf 12, see Figs. 2 and 3, adapted to be fixedly secured to the side wall 4 of the trunk, and a swinging member 13 pivoted to the front end of the leaf 12 and 65 adapted to carry the garment hangers 9, as subsequently described. It is preferable to form said member 13 from a single piece of sheet metal bent into channel shape longitudinally along its middle 14 and providing 70 at its margins feet or flanges 15, 15 in substantially the same plane and on opposite sides of the channel portion. The horizontal projecting rib or middle portion 14 provides a series of vertical sockets 16 arranged 75 at suitable distances apart and each formed by alined holes in the upper and lower sides of said projecting portion. Preferably, at one end of the said member 13, the flanges 15 are extended beyond the middle channel 80 portion 14 as at 17, and wrapped around a hinge pin 18 to which the adjacent end of the leaf 12 is similarly connected, see Fig. 3, said extensions 17 being returned upon the flanges 15 and secured by rivets 19 or 85 equivalent means thereto. The leaf 12 attached horizontally to the side wall 4 forms a rigid brace for strengthening the trunk, in addition to providing a pivotal mounting for the swinging member 13. A stop 90 20 may project from the exposed surface of the leaf 12 adjacent its inner end or end away from the hinge, so as to limit the inward swing of the member 13 into substantially parallel relation thereto in closed position, said stop also acting as a support for 95 the free end of the swinging member if it be so desired. Also, in forming the hinge extension 21 on the leaf 12 it is preferable to produce a shoulder 22 therein which projects outwardly beyond the end of the leaf and lies in the path of the member 13 so as to limit its outward swing, as shown in 100 Fig. 3. Such limitation is preferably to prevent the member 13 from swinging out 105 farther than the plane of the open front, but obviously such limitation may be made to any degree desired and may be caused by a stop otherwise positioned than the particular one herein shown. 110

I have shown the hangers, for purposes of illustration, consisting each of two flat strips 23, 23 arranged vertically edgewise and adapted to clamp between themselves a garment such as the trousers 10 which are shown, the outer ends of said strips being releasably held together by a clip 24 of any ordinary and well-known type. It will be understood, however, that any other form 10 of hanger adapted to support garments or the like might be substituted for the one which I have specifically shown, without departing from the spirit and scope of the invention.

15 For pivotally connecting each hanger to the swinging member 13, the same is provided at its inner end with a head 25 as shown in detail more particularly in Figs. 4 and 5. This head is preferably stamped 20 out of a single piece of sheet metal doubled together so that its opposite ends 26, 26 together form a sleeve to fit over the ends of the strips 23, 23, rivets 27 or equivalent clamping means securing it thereto. Extending 25 from said sleeve in the opposite direction from said strips, the head 25 provides a neck 28 which connects the sleeve to a transversely upright pivot 29 formed at the doubled edge of the head, and which 30 projects upward above the neck as at 30 and also downward below said neck as at 31 sufficiently to pass entirely through the rib 14 of the swinging member 13, allowing the neck to rest edgewise on the top of said rib, 35 as shown in Fig. 1. It is preferable to stamp the pivot 29 into cylindrical shape with conical or tapered ends, as shown, so as to permit readily inserting the same into the sockets 16 and mounting the hanger to swing 40 freely on the member 13. The neck 28 is preferably of less height than the sleeve formed by the ends 26, 26 and projects from the same adjacent the top thereof, although it will be understood that I do not limit myself to such details.

The upper end 30 of the pivot 29 prevents 45 by its engagement with the top 6 of the trunk removal of the pivot from its seat or bearing, except when the swinging member 50 13 is in its extreme forward position, and thus the hinged ends of the hangers are secured against dislodgment during shipment of the trunk.

The bracket 11 I have shown made of 55 strap iron with its forward end 32 rounded and overlapping feet 33, 34 at its rear end which are riveted or otherwise firmly secured to the back 3 of the trunk in vertical position at a little distance from the side 60 wall 5, so that there will be no uncertainty about the free ends of the hangers 9 overlying the bracket. The hangers readily swing into closed position overlying said bracket as the swinging support member 13 is pushed back against the side wall 4, and 65 the garments depend from said hangers between the bracket and swinging support. The bracket 11 being free from the adjacent side wall of the trunk enables a hand to be inserted between it and said side wall, as for 70 instance to unfasten the clasp of one of the hangers 9 and release the garment held thereby without swinging all of the hangers out into the room.

Obviously, various modifications in detail 75 construction can be made by those skilled in the art, without departing from the spirit and scope of my invention, and I do not wish to be understood as restricting myself except as required by the following claims 80 when construed in the light of the prior art.

Having thus described the invention, what I claim is:

1. The combination with a trunk, of a garment hanger support comprising a leaf 85 fixed firmly to the side of said trunk, a swinging member having a middle rib with flanges on opposite sides thereof extending at one end of the member beyond said middle rib, a hinge pin on said leaf around 90 which pin said extending flanges are hingedly wrapped, and a shoulder on one of said members adapted to engage the other and limit the outward swing of the swinging member. 95

2. The combination with a trunk, of a garment hanger support comprising a leaf 100 fixed firmly to the side of said trunk transversely thereof and extending substantially the depth of said side bracing the same, a swinging member having a middle rib with flanges on opposite sides thereof extending at one end of the member beyond said middle rib, a hinge pin on said leaf around 105 which pin said extending flanges are hingedly wrapped, and a shoulder on one of said members adapted to engage the other and limit the outward swing of the swinging member. 110

3. In a trunk, the combination with a 115 socketed support hingedly mounted thereon to swing in a plane parallel and adjacent to the top of the trunk, of a garment hanger having a head with a transverse pivot at the end thereof projecting both upward and downward, the lower end of said pivot adapted to enter a socket of said support and the upper end adapted to engage the top of the trunk and prevent removal of the lower end from its socket when the support lies beneath the trunk top. 120
